UNITED STATES PATENT OFFICE.

THOMAS OLIVER KAHSE, OF ROCHESTER, NEW YORK, ASSIGNOR TO WARREN-KAHSE, INCORPORATED, OF ROCHESTER, NEW YORK, A CORPORATION OF NEW YORK.

DESIGN FOR A BADGE.

Application filed June 4, 1923. Serial No. 6,388. Term of patent 14 years.

To all whom it may concern:

Be it known that I, THOMAS OLIVER KAHSE, a citizen of the United States, residing at Rochester, in the county of Monroe and State of New York, have invented a new, original, and ornamental Design for Badges, of which the following is a specification, reference being had to the accompanying drawing, forming part hereof.

The figure is a perspective view of an emblem showing my new design.

I claim:—

The ornamental design for a badge or similar article as shown.

In witness whereof, I hereunto subscribe my name this 31st day of May A. D. 1923.

T. OLIVER KAHSE.
